UNITED STATES PATENT OFFICE.

CLARENCE D. WILSON, OF COLUMBUS, OHIO.

DESIGN FOR A TELEPHONE-RECEIVER HOLDER.

SPECIFICATION forming part of Design No. 32,162, dated January 30, 1900.

Application filed January 3, 1900. Serial No. 294. Term of patent 7 years.

To all whom it may concern:

Be it known that I, CLARENCE D. WILSON, a citizen of the United States, residing at Columbus, in the county of Franklin and State of Ohio, have invented and produced a new and original Design for a Telephone-Receiver Holder; and I do hereby declare the following to be a full, clear, and exact description of the same, reference being had to the accompanying drawings, forming a part thereof.

In said drawings, Figure 1 is an edge view of the holder according to my design. Fig. 2 is a view looking toward the under side thereof. Fig. 3 is a view looking toward the front of the holder.

As shown in the drawings, the holder is composed principally of two portions, to wit: a standard or plate 1 and a bracket or holder proper,² standing in a plane substantially at right angles to the plate 1. The bracket is composed of a shank 3 and two arms 4 and

4^a, extending therefrom and diverging with respect to each other first outwardly, then inwardly, and finally outward and upward. ²⁵ The extremities of these arms are rounded, as indicated at 5 and 5^a. The standard or plate 1 at its extremity has lateral projections 6 and 6^a and an end projection 7. This plate is also shown to have circular openings in the projections 6 and 6^a and near the junction of the plate with the shank 3; but the leading or important feature of my design is the arms 4 and 4^a, shaped as shown and described, in connection with a standard or plate 1. ³⁰ ³⁵

What I claim is--

The design for a telephone-receiver holder as herein shown and described.

In testimony whereof I affix my signature in presence of two witnesses.

CLARENCE D. WILSON.

Witnesses:

GEORGE W. ALFRED,
GEO. M. FINCKEL.
